US00D834817S

(12) **United States Design Patent** (10) **Patent No.:** **US D834,817 S**
(45) **Date of Patent:** **** Dec. 4, 2018**

(54) **BAG**

(71) Applicant: **Milwaukee Electric Tool Corporation**,
Brookfield, WI (US)

(72) Inventors: **Christopher S. Hoppe**, Milwaukee, WI
(US); **Steven W. Hyma**, Milwaukee,
WI (US); **Grant T. Squiers**, Cudahy,
WI (US); **Michael Stearns**, Milwaukee,
WI (US)

(73) Assignee: **MILWAUKEE ELECTRIC TOOL
CORPORATION**, Brookfield, WI (US)

(**) Term: **15 Years**

(21) Appl. No.: **29/533,521**

(22) Filed: **Jul. 17, 2015**

(51) LOC (11) Cl. **03-01**

(52) U.S. Cl.

USPC **D3/263; D3/905**

(57) **CLAIM**

We claim the ornamental design for a bag, as shown and described.

DESCRIPTION

FIG. 1 is a front perspective view of a bag.

FIG. 2 is a front view of the bag shown in FIG. 1.

FIG. 3 is a rear view of the bag shown in FIG. 1.

FIG. 4 is a right side view of the bag shown in FIG. 1.

FIG. 5 is a left side view of the bag shown in FIG. 1.

FIG. 6 is a top view of the bag shown in FIG. 1.

FIG. 7 is a bottom view of the bag shown in FIG. 1.

FIG. 8 is a front perspective view of the bag shown in FIG. 1 with the front pocket open.

FIG. 9 is a top view of the bag as shown in FIG. 8; and,

FIG. 10 is a front view of the bag as shown in FIG. 8.

Portions of the bag shown in broken lines are included for the purpose of illustrating environment and form no part of the claimed design.

1 Claim, 10 Drawing Sheets
